UNITED STATES PATENT OFFICE.

FREDERICK W. PENDERGAST, OF CAMBRIDGE, MASSACHUSETTS.

BROOM.

1,139,716.

Specification of Letters Patent. Patented May 18, 1915.

Application filed July 10, 1914. Serial No. 850,085.

To all whom it may concern:

Be it known that I, FREDERICK W. PENDERGAST, a citizen of the United States, and resident of Cambridge, in the county of 5 Middlesex and State of Massachusetts, have invented certain new and useful Improvements in Brooms, of which the following is a specification.

This invention has for its object to provide a strong and durable broom of simple and relatively inexpensive construction, and adapted to be manufactured by blind workmen.

The invention consists in the improved 15 construction which I will now proceed to describe and claim.

Of the accompanying drawings forming a part of this specification: Figure 1 represents a side elevation, partly in section, of 20 my improved broom; Fig. 2 represents a section on line 2—2 of Fig. 1; Fig. 3 represents a sectional view illustrating a part of the operation of assembling the parts; Fig. 4 represents a perspective view of one 25 of the bunches of broom filaments herein-after referred to; Fig. 5 represents a section on line 5—5 of Fig. 1.

The same reference characters indicate the same or similar parts in all the views.

30 In the drawings, 12 represents the broom head, which is preferably a strip or block of wood having in one side a groove 13 extending lengthwise of the head, the outer ends of the groove forming shoulders or 35 abutments 14.

In the ends of the groove 13 are placed the inner ends of two bunches 15 of flexible broom filaments, which may be elongated strips of rattan or other material commonly 40 used in the manufacture of brooms; each bunch being preferably formed by assembling a group of filaments and folding the same centrally to form a neck portion 15^a, which is reinforced and confined by a wrapping 45 15^b of cord or string. The neck portions are pressed closely against the shoulders 14 and confined independently by suitable means such as nails 16 driven through the said neck portions and through the 50 portions of the head which form the sides of the groove 13. Said neck portions may be additionally secured by glue if desired.

18 represents a key, preferably of wood, formed to enter the groove 13 between the 55 bunches 15, the ends of the key forming shoulders 19 which bear closely against the

neck portions 15^a, said portions being compressed between the shoulders 14 and 19.

Before inserting the key in the groove a layer 20 of broom filaments is placed on the head with the filaments extending across the groove 13, as shown by Fig. 3, and the key 18 is placed on said layer. The cross sectional area of the key is considerably less than that of the groove, as shown by Figs. 2 and 3. The key and portions of the layer 20 are next forced into the groove 13, the central portions of the filaments being thus bent and conformed to the back and two sides of the key and the end portions of said filaments being caused to project from the head, as shown by Figs. 1 and 2. The key 18 and the filament portions confined thereby are now secured to the head by nails 21, and if desired they may be additionally secured by glue.

The central portion of the head 12 may be provided with a socket to receive a handle 22.

The bunches 15 bear on the opposite 50 edges of the layer 20 and cover the ends of the V-shaped space adjacent to the key 18 between the outwardly extending portions of said layer, so that there are no openings at the ends of the broom for the admission 55 of dust and dirt, the bunches 15 forming substantial additions to the brush material formed by the layer 20. The neck portions of the bunches 15 are confined not only by the nails 16 and the glue which may be 60 employed, but also by the ends of the key, the length of the key being such that the operation of inserting it into the groove causes the ends of the key to exert clamping 65 pressure on the neck portions 15^a.

Having described my invention, I claim:

1. A broom comprising a head having a longitudinal groove in one side, a key formed to enter said groove and a layer of brush filaments extending across the 100 back of the key and bent outwardly across opposite sides of the key by the operation of inserting the key in the groove, the key and the filaments engaged therewith being secured in the groove, and bunches of brush 105 filaments secured in opposite ends of the groove and bearing on the edges of said layer, said bunches covering the ends of the spaces adjacent to the key between the outwardly extending portions of said layer.

2. A broom comprising a head having a longitudinal groove in one side, bunches of

brush filaments inserted and independently fastened in the end portions of said groove, a key formed to enter the groove between said bunches, and of such length that its ends bear on the bunches and press the same against the ends of the groove, and a layer of brush filaments extending across the back of said key and bent outwardly across opposite sides of the key by the operation of inserting the key in the groove, the key and

the filaments engaged therewith being independently secured in the groove.

In testimony whereof I have affixed my signature, in presence of two witnesses.

FREDERICK W. X PENDERGAST.
